PIPE WRAPPING MACHINE

Robert Gregory Roberts, Kansas City, Mo., assignor to The Barrett Company, New York, N. Y., a corporation of New Jersey

Application October 21, 1932, Serial No. 638,891

4 Claims. (Cl. 242—11)

This invention relates to apparatus for placing a protective covering on pipes or other tubular articles hereinafter referred to as pipes and especially relates to a machine for wrapping protecting material such as bitumen- or resin-saturated felt or paper or other types of saturated or unsaturated flexible shields spirally around a pipe.

One object of the invention is to provide a pipe wrapping machine of relatively simple design and construction which can be manufactured at a minimum cost.

Another object of the invention is to provide a compact, durable machine of light weight which is economical to operate and which can readily be adjusted to accommodate different size pipes and wrap them with different amounts of overlap between contiguous windings.

Another object of the invention is to provide a compact machine which does not revolve around the pipe but travels longitudinally along the top thereof and thus eliminates the necessity of jacking up the pipe to any considerable height during the wrapping operation to provide the necessary clearance beneath the pipe to permit the machine rotating around the pipe to pass thereunder.

Other objects and advantages will appear from the following detailed description of this invention.

In the laying of pipe lines, especially underground lines, it is customary to apply a protective coating and wrapping to the pipes to prevent corrosion and rapid deterioration. Heretofore the apparatus employed for wrapping pipe involved a circular machine which was fitted onto the pipe and then rotated around it. In employing such apparatus the pipe must necessarily be jacked up to a considerable height to allow ample clearance beneath the pipe for the passage of the wrapping machine thereunder during its rotation. The jacking of the pipe involves arduous and time-consuming labor.

In this invention the pipe is merely placed on a rolling rig or other apparatus for rotating the pipe and is wrapped by a simple machine which does not revolve about the pipe but merely rests on it. The rotation of the pipe imparts a longitudinal movement to the wrapping machine, the wrapping material being fed to the pipe and spirally wrapped thereabout.

For a better understanding of the invention, reference should be made to the accompanying drawings, wherein is shown, by way of illustration, a preferred embodiment of the invention.

In the drawings:

Fig. 1 is a plan view of a pipe wrapping machine embodying this invention;

Fig. 2 is a side elevation of the apparatus of Fig. 1;

Fig. 3 is an end elevation showing the carriage frame, guide bars, and idler wheels;

Fig. 4 is an end elevation showing one type of driving mechanism of a rolling rig for rotating the pipe;

Fig. 5 is a side elevation of the apparatus showing an alternate method of construction;

Fig. 6 is a fragmentary side elevation of a pipe wrapping machine showing a modified support for the wrapping material; and

Fig. 7 is an end elevation of the apparatus of Fig. 6.

The pipe wrapping machine of this invention comprises a semi-circular carriage or frame 1 composed of side angle-bars 2, 3, joined by cross-members 4. Mounted on the frame are idler wheels 5 which contact with a pipe 6, the weight of the carriage being thus carried by the pipe. The pipe 6 on which the carriage rests is itself supported and rotated by rolling rigs 7 herein-after more fully described. As the pipe is rotated the movement of the pipe surface past the contacting idler wheels 5, whose axes of rotation may be set at an angle to the axis of the pipe, causes the carriage, which may be held in a horizontal position on the pipe by the operator, to move longitudinally along the pipe. This longitudinal movement of the carriage and the rotation of the pipe cause wrapping material 8 to be unwound from spool 9 and to be spirally wrapped around the pipe. The spool is held on an extension of spindle 10, which is supported on the carriage.

As shown in Fig. 3, the idler wheels 5 are connected to the semi-circular angle-bars 2 and 3 of the carriage by means of guide bars 11 which extend radially inward from the angle bars. Two brackets or clamps 12 are provided on each angle bar 2 or 3, in the neighborhood of the extremities thereof. The guide bars 11, which are preferably L-shaped, are slidably mounted in clamps 12 and may be secured in adjusted position by tightening bolts 13 passing through the clamps. These clamps and guide bars permit the adjustment of the idler wheels toward or away from the angle-bars to suit the size of the pipe being wrapped. Thus, one size machine can be utilized for wrapping several sizes of pipe; as, for example, one machine may be made suitable for wrapping pipe of 8, 10, 12, and 14 inch diameter; 65

another larger machine may be adapted to wrap pipe of 16, 18, and 20 inch diameter, etc. Graduations may be provided on the guide bars so that the exact settings for various sizes of pipe can 5 readily be made.

The wheels 5, which are preferably rubber tired, are mounted in supports or yokes 14 pivotally secured to the extensions of the guide bars. This permits a pivotal adjustment of supports 14 10 and the idler wheels 5 relative to the guide bars. To obtain the same overlap between contiguous windings with different size pipe, it is necessary to adjust the angular position of wheels 5 with respect to the longitudinal axis of the pipe. 15 In accordance with this invention, any desired setting to permit the wrapping of different size pipes with substantially the same overlap between contiguous windings can easily be made by matching indicators 15 on the wheel supports 20 or yokes 14 with the angular graduation 15' at the bases of the guide bars 11 (Fig. 3). The longitudinal movement of the carriage with respect to the rotation of the pipe is governed by the setting of these idler wheels; the greater the pitch, 25 or angle between the axis of the pipe and the axes of the wheels, the greater will be the relative longitudinal movement.

The spool 9 of wrapping material, which may be felt, foil, paper, etc. is held in place on an 30 extension of the spindle 10 projecting from one side of the carriage frame, by guide discs 16 and 17. Disc 16 can be securely positioned on the spindle by means of set screw 18 which passes through its hub. The disc 17 holding the other 35 side of the spool is kept in place by the compression spring 19, the compression of which is regulated by a hand-wheel 20 which screws on a threaded portion of the spindle. This arrangement permits a spool of wrapping material of any 40 desired width to be rapidly positioned on the spindle. Moreover, the tautness or tension of the wrapping material between the pipe and the spool can be changed and regulated merely by turning the hand-wheel 20 which, through the 45 compression spring 19, governs the pressure of the guide disc 17 against the spool.

The spindle 10, which holds the spool of wrapping material, is composed of two sections 10-10 held together by the universal joint 21, and is 50 supported from the carriage frame by the clamps 22. As shown, the clamps comprise bases 23 which may be bolted or otherwise secured to the carriage frame. Spindle supports 24 are pivotally mounted on the bases 23 by means of pins 55 40 extending through bases 23. Pivotally mounted in the spindle supports 24 are bearings 25, through which the spindles pass. This mounting and the universal joint 21 permit the angular adjustment of the spindle extension carrying the 60 spool of wrapping material in all planes. The necessary angular setting of the extension required by operating conditions (e. g. size of pipe, width of shield and amount of overlap) may be rigidly fixed by means of set screws 26 engaging 65 pins 40 and set screws 27 engaging the spindle sections or equivalent clamping device.

In Figs. 1 and 2, the spindle is shown in one position. It will be noted that the spindle may be adjusted in both vertical and horizontal planes, 70 the preferable setting in both planes being dependent upon the size of the pipe being wrapped and the amount of overlap between contiguous layers of wrapping desired. The wrapping material should leave the spool in a direction substantially perpendicular to the direction of the

axis of the spool. Fig. 5 shows an alternate type of apparatus in which the spindle used for holding the wrapping is suspended under the carriage frame rather than above it as shown in Figs. 1 and 2.

Figures 6 and 7 show a modified construction for supporting the wrapping material on the machine. The spool 9 of wrapping material is held in place on a spindle 40 supported at both ends by a frame 41. This frame is in turn supported from angle bar 2 by a suitable bracket 42 riveted or otherwise secured to the angle bar. A universal joint 43 of the ball and socket type may be employed to rigidly fix the frame 41 and spindle 40 in any desired position. Set clamp 44 of the universal joint may be used to lock the assembly in the desired position. Although the universal joint is shown in the drawings as a ball and split-socket joint, other types of universal joints could be used. As the wrapping material 8 is unwound from the spool it passes through a set of tension rollers 45 suitably supported from frame 41. The pressure of the rollers on the wrapping material can be adjusted by means of spring 46 confined in casing 47 and pressing against the bearing block in which one of the rollers 45 is mounted and adjusting screw 48 which regulates the pressure exerted by the spring. Thus any desired tension on the wrapping material being fed to the pipe can be obtained.

Fig. 4 shows a hand-actuated rolling rig 7 which may be used for supporting the pipe and imparting a rotary movement to it. The pipe rests at both ends on the rollers 29 and 30 which are mounted in supports 31 and 32, respectively. Rollers 30, at the right end of Fig. 2, are mounted on shafts having keyed thereon the sprocket wheels 33 (Fig. 4). As the crank 34, on a shaft having the sprocket 35 keyed thereon, is turned, the sprocket chain 36 is moved, driving the sprocket wheels 33, causing the rollers 30 and pipe 6 to rotate. Although this particular rolling rig is herein shown, any other suitable hand- or machine-actuated mechanism for rotating the pipe may be used, as, for example, belts passing over pulleys and carrying the pipe may be substituted for the flanged rollers and one set of pulleys driven to rotate the pipe.

In operation, the guide bars 11 and idler wheels 5 are adjusted through the guide bar clamps 12 to suit the size of pipe to be wrapped. The idler wheel supports 14 are also adjusted pivotally relative to the guide bars to regulate the pitch of the idler wheels and so govern the longitudinal movement of the carriage and the amount of overlap of contiguous windings. The machine or carriage is then placed in a saddle fashion on the pipe to be wrapped, which is supported on a suitable rolling rig.

The wrapping material 8, which may first be wrapped around the pipe once or twice by hand to hold it in place when the wrapping operation is begun, is then adjusted on the spindle 10. By adjusting the spindle through the universal joint 21, universal spindle clamps 22 and set screws 26 and 27, the roll of wrapping material can be adjusted angularly so that the material will be applied to the pipe evenly and without wrinkles or buckles. The desired tension of the wrapping material can also be regulated through the hand-wheel 20 and compression spring 19, thereby permitting the material to be applied to the pipe surface with the desired tightness. The carriage is then held in a horizontal position, as for example 75

by holding the cross-bars 4, and the pipe is made to rotate on the rolling rig. The movement of the pipe past the contacting idler wheels, which are set at a pitch, causes the machine to move 5 longitudinally along the pipe. The rotary motion of the pipe and longitudinal movement of the carriage carrying the wrapping material causes the material to be spirally wound around the pipe, the pitch of the spiral being substantially 10 the same as the pitch at which the idler wheels are set. The idler wheels in passing over the wrapping directly as it is applied exert pressure thereon and thus eliminate unevenness or wrinkles in the wrapping. As the carriage moves 15 along the pipe, the men who are carrying out the operation walk along also and hold it horizontally on the pipe. In stopping the wrapping operation the rotation of the pipe is discontinued, the wrapping material is severed between the 20 pipe and the roll, and the machine is lifted off the pipe. Alternatively mechanical means, such as guide rods, may be provided to prevent rotation of the wrapping mechanism without limiting its longitudinal movement, thereby allowing it to 25 travel along the pipe when the latter is rotated.

It is evident that the apparatus of this invention makes the pipe wrapping operation comparatively simple to perform. It also permits the operation to be carried out simultaneously with a 30 pipe coating procedure since the rolling rigs which are used for rotating the pipes during the coating procedure will also serve to supply the motive power necessary for the wrapping operation.

Under certain conditions in the field a preferred method of applying wrapping in accordance with this invention is to apply an unbonded wrapping, that is, one that is not cemented to or bonded with coating on the pipe. When some types of shields and enamels are used, abrasion, 40 shearing, or puncture of unbonded wrapping is less likely to result in scarring or removal of the enamel than if the wrapping is bonded with such coating.

Coating material, such as fluid bitumen, may be poured onto the top of the pipe, while the pipe is rotating, by one or more operators moving 45 along the pipe. In applying unbonded wrapping, the wrapping machine should follow the coating gang at such an interval as to give the enamel time to set before application of the wrapping. When a bituminous coating, such as the pitch 50 composition of Eckert Patent 1,773,131, is used, it is applied to the pipe hot and molten. The body of the pipe rapidly absorbs and disperses the 55 heat of the coating, thereby causing it to solidify and set very rapidly. Under such conditions the wrapping apparatus may be made to follow closely the coating gang, even in the application of unbonded wrapping.

When conditions make it desirable to apply a bonded wrapping, the apparatus should be used immediately following the coating operation, the setting of the coating causing the wrapping to adhere firmly to the pipe and bond with the coating 65 thereon. In the application of a bonded wrapping a slower setting enamel or other coating is advantageously used.

In connection with the foregoing description and illustration of the construction and operation 70 of this invention, it should be understood that these are merely for the purpose of clarifying an understanding thereof. Although as described the

carriage may be held on the pipe by hand, an outrigger wheel or wheels may be secured to the frame, thereby making it unnecessary for the operator to hold the machine. Other possible modifications include the use of a greater or lesser 5 number of friction wheels than shown in the drawings or the placement of the spool of wrapping material on the spindle between the angle-bars rather than on the spindle extension. Various modifications of the forms and arrangements of the parts may be made without departing 10 from this invention.

It will be noted that the wrapping machine of this invention is simple, compact, inexpensive to construct and operate, and is movable longitudinally of the pipe but is not rotated about the pipe. Hence, it eliminates the difficulties of jacking and removing pipe from the jacks necessary with prior existing pipe wrapping machines which were rotated about the pipe. Further, due to the adjustable mounting of the wheels 5 and the spindle containing the wrapping material, different size pipes may be wrapped with the same amount of overlap between contiguous windings and the amount of overlap between contiguous windings on the pipe may be 15 adjusted as desired with one and the same wrapping machine.

I claim:

1. A pipe wrapping machine comprising a carriage adapted to be placed on a rotating pipe, 30 wheels supported from the frame of said carriage contacting with the pipe and supporting the carriage on the pipe, means for rotating the pipe, a spindle mounted at the top of the frame 35 of said carriage and supported on opposite sides of the carriage, said spindle having an extension projecting from one side of the carriage frame and providing a support for the wrapping material, the portion of said spindle between said 40 opposite sides of the carriage being jointed to permit angular adjustment of the projecting portion.

2. A wrapping machine comprising a carriage, 45 rotatably and pivotally adjustable bearings mounted on opposite sides of the carriage, a spindle comprising two sections joined together by a universal joint, said spindle being supported on the carriage by the adjustable bearings which engage the spindle on both sides of the universal 50 joint, one section of the spindle having an extension for maintaining a supply of wrapping material.

3. A wrapping machine comprising a carriage, 55 rotatably adjustable bearings mounted on opposite sides of the carriage, a spindle comprising a pair of sections connected together by a joint, said spindle being supported on the carriage by the adjustable bearings which engage the spindle on opposite sides of the joint, one section of 60 the spindle being adapted to hold a supply of wrapping material.

4. A wrapping machine comprising a carriage, 65 pivotally adjustable bearings mounted on opposite sides of the carriage, a spindle comprising a pair of sections connected together by a joint, said spindle being supported on the carriage by the adjustable bearings which engage the spindle on opposite sides of the joint, one section of 70 the spindle being adapted to hold a supply of wrapping material.

ROBERT GREGORY ROBERTS.
